COMBINATION LOCK

Richard W. Armstrong, Rockville, Md., assignor to the United States of America as represented by the Secretary of the Army

Filed Apr. 23, 1965, Ser. No. 450,551
5 Claims. (Cl. 70—303)

ABSTRACT OF THE DISCLOSURE

This invention relates to an improved combination lock having a spring biasing means for axially moving a driver-shutter assembly out of engagement with a detent to eliminate noise, drag and wear during normal combination dialing associated with a combination lock similar to the one described in U.S. Patent No. 3,073,145, issued January 15, 1963, to Anthony J. Potzick.

This invention may be manufactured and used by or for the Government for governmental purposes without the payment to me of any royalty thereon.

This invention relates to a combination lock and more particularly to an improvement in an uncontrolled-motion, manipulation-resistant lock. The invention is related to and constitutes an improvement over the invention disclosed in United States Patent No. 3,073,145. The improvement is concerned with eliminating the rather loud noise and rotational drag produced when the combination of the Potzick lock is dialed. By means of this improvement, the Potzick lock will operate more smoothly and quietly and with reduced wear.

The noise and rotational drag associated with the Potzick lock are caused by an uncontrolled-motion shutter which is attached to the wheel driver to prevent the angle bar nose from engaging the edges of the driver notch. The shutter is provided with detent notches which coact with a detent mechanism to operate the shutter. A detailed statement of the structure and operation of the shutter mechanism and its use in preventing manipulation to determine the location of the wheel gates is contained in U.S. Patent No. 3,073,145. The improvement of this invention consists in axially moving the driver-shutter assembly out of vertical alignment with the detent mechanism during the combination dialing operation, thus eliminating the detent noise, drag and wear. After a combination is dialed, the driver-shutter assembly is returned to vertical alignment with the detent and the dial is turned to engage the angle bar and withdraw the lock bolt. It is only after a combination is dialed and while the dial is being turned to engage the angle bar that the shutter mechanism is required to prevent manipulation.

An object of the invention is to provide an uncontrolled motion, manipulation-resistant lock, the combination of which can be dialed smoothly and noiselessly without lessening the security of the lock.

Another object is to provide a combination lock whose driver-shutter assembly can be moved axially in or out of vertical alignment with an anti-manipulation detent mechanism so that the detent mechanism is not operated except when the lock fence tests whether the wheel gates have been properly aligned.

Another object is to lessen the wear on the driver-shutter-detent mechanism of an uncontrolled-motion, manipulation-resistant lock.

The structural features of the invention are illustrated in the accompanying drawings in which:

FIG. 1 is a top view of a combination lock of the type to which this invention relates;

2

FIG. 2 is a cross-sectional view of a preferred driver-shutter-detent assembly taken on line 2—2 of FIG. 1;

FIG. 3 is an elevation view, partly broken away, of the assembly shown in FIG. 2, the wheels, gates, fence and angle bar nose being shown in phantom; and

FIG. 4 is a side view, partly broken away, of the assembly shown in FIG. 3.

Referring to the drawings, FIG. 1 generally illustrates the combination lock 1 to which this invention relates.

10 The lock is shown mounted to a safe door 2. Lock 1 comprises a rotatable dial 3, and an index 4 located on the outside of door 2. Secured to the inside of door 2 is case 5 containing lock mechanism 6. Case 5 has a removable back portion 7. Lock bolt 8 is shown extending 15 through case 5 for engagement with a bolt receiving member in the body of the safe, not shown.

Referring to FIG. 2, the lock mechanism comprises a shaft 9, a spring 10, a shutter 11, a driver 12, a plurality of wheels 13 and a detent 14. Shaft 9 is fastened to and 20 rotatable with dial 3 and it extends through door 2 and case 5 to operate lock mechanism 6. Driver 12 is secured to shaft 9 by a key 15 having a pair of spaced legs 16 which are received in diametrically spaced grooves 17 and 18 (FIG. 3) formed in shaft 9 and hub 19 of driver 12. 25 Hub 19 extends on both sides of driver 12. Drive pin 20 extends from the inner face of driver 12 to engage the first of a plurality of wheels 13.

Shutter 11 is rotatably mounted on hub 19 and is held 30 in place by spring clip 21. Shutter 11 has a central hub 22 and a peripheral rim 23 which extends on both sides of the central disk 24. Rim 23 and hub 22 are closely adjacent driver 12 and together with driver 12 and disk 24 define a cavity within shutter 11. A torsion spring 25 intercouples shutter 11 and driver 12. Spring 25 fits around 35 hub 22 and is hooked around spring pins 26 and 27 located on driver 12 and shutter 11, respectively (FIG. 4). Pins 28 and 29 on shutter 11 are slightly longer than pin 26 and serve as stops to limit the rotation of shutter 11 with respect to driver 12. The functioning of pins 28 and 29 is 40 more fully described in U.S. Patent No. 3,073,145. Detent notches 30, 31 and 32 are formed in the inner periphery of rim 23, that is, on the side nearest driver 12. Rim 23 forms a smooth and continuous band around shutter 11 on the side nearest spring 10.

45 Detent 14, made up of housing 33, spring 34, plate 35 and ball 36, is of the same structure as the detent shown in United States Patent No. 3,073,145. Likewise, the configurations of driver 12, shutter 11, wheels 13, angle bar nose 37 and fence 38 are essentially the same as those structures shown in Patent No. 3,073,145 and the functions of these structures are explained in detail in that patent. There are several important structural differences 50 between this invention and the invention disclosed in Patent No. 3,073,145, however, and these differences will now be described in detail.

55 Shutter 11 has been modified by extending rim 23 past disk 24 on the side of shutter 11 facing spring 10. Spring 10 has been added to the Potzick lock between case 5 and shutter 11 to force the driver-shutter assembly out of vertical alignment with detent 14 during normal combination dialing. Shaft 9 is also forced inwardly by the action of spring 10. Rim 23, as extended, forms a smooth continuous surface upon which angle bar nose 37 rides when the driver-shutter assembly is rotated in the normal position, 60 which is out of alignment with detent 14. The driver-shutter assembly can be moved axially into alignment with detent 14 by pulling dial 3 out against spring 10.

65 To maintain the increased security described in Patent No. 3,073,145, however, the driver-shutter assembly must not be pulled toward case 5 when the dial setting is within approximately 10 degrees of either side of zero. In this

area, pulling the driver-shutter toward case 5 would allow manipulative readings to be made as the dial is rotated and angle bar nose 37 dips toward the notch of driver 12. To avoid this security problem, sector 39 has been added to driver 12. Sector 39 overrides stop 40 during an increment of rotation of approximately 20 degrees. Stop 40 extends from case 5 and is so located that sector 39 overrides the stop during the increment of dial rotation which extends approximately 10 degrees on either side of the zero setting. These settings reflect the increment of rotation during which the driver notch is rotationally aligned under angle bar nose 37. The extension of rim 23, and the addition of spring 10, sector 39 and stop 40 constitute the essential structural changes over the Potzick lock.

In operation, the combination of the lock is dialed with the driver-shutter assembly in its normal position, out of vertical alignment with detent 14. Assuming the combination to be the 3-number combination, 25-50-30, the operator would dial the combination with the driver-shutter in normal position. During this dialing, detent notches 30, 31 and 32 would not come in contact with detent 14 and the dial would turn quietly, without rotational drag and with no wear on either the detent or the detent notches. After the combination is dialed, the dial must be returned from "30" to zero so that fence 38 can drop into the gates of wheels 13 and angle bar nose 37 can drop into the driver notch. The operation of returning from "30" to zero is performed with the driver-shutter in vertical alignment with detent 14 and with the driver notch in vertical alignment with angle bar nose 37. The alignment is brought about by the operator's pulling out on dial 3 thereby compressing spring 10. Detent 14 is engaged during this return. At the zero setting, angle bar nose 37 drops into the driver notch and, upon further rotation of the driver, the angle bar, which is attached to the lock bolt, moves to withdraw the bolt into case 5, the sector 39 preventing the driver-shutter from returning to its normal position during an increment of dial movement of approximately 10 degrees on either side of zero.

By the improvement of this invention, the Potzick lock and similar type locks can be made to operate quietly and without rotational drag or detent wear. At the same time, there is no diminishing of the security of the Potzick lock since the detent is engaged during the crucial period of the return to zero at the end of the combination dialing and since stop 40 prevents a rotational and vertical alignment of angle bar nose 37 and the driver notch without detent contact.

I claim:

1. In a combination lock having a rotatable dial, a shaft rigidly connected to said dial, a plurality of rotatable wheels, a driver rigidly connected to said shaft for en-

gaging one of said wheels, a shutter interconnected to and rotatable with and with respect to said driver and having detent notches along a portion of its periphery, an angle bar having a nose which is supported by the periphery of said shutter throughout a portion of each revolution of said shutter and a detent which is in alignment with and which engages and disengages with the detent notches of said shutter as the shutter rotates, said engagement and disengagement imparting a motion to said shutter which is not controllable by the lock operator, the improvement which comprises:

(a) means for axially moving the shutter a sufficient distance to disalign the detent notches of said shutter and said detent during normal combination dialing, said means allowing the detent notches of said shutter to be moved into alignment with said detent during a portion of the combination dialing operation, including the final opening operation; and

(b) means for continuously supporting the nose of said angle bar during rotation of said shutter when said shutter is disaligned with said detent.

2. The combination lock improvement described in claim 1 wherein said means for moving said shutter is a resilient means and wherein said means for continuously supporting the nose of said angle bar comprises a smooth continuous rim attached to said shutter.

3. The combination lock described in claim 1 wherein said improvement further comprises means for preventing the axial movement of said shutter during a portion of the rotation of the combination dial.

4. The combination lock improvement described in claim 3 wherein said means for preventing axial movement of said shutter during a portion of the rotation of the combination dial comprises a sector attached to said driver and a stop attached to the lock frame, said sector and stop being so located that the sector overrides the stop during a portion of the dial rotation to prevent movement of said driver and shutter relative to said stop.

5. The combination lock improvement described in claim 4 wherein said sector and said stop are located so as to prevent axial movement of said shutter during approximately 20 degrees of rotation, said 20 degrees being the 10 degrees on either side of the zero setting of the combination dial.
